UNITED STATES PATENT OFFICE.

GOTTFRID PERSSON, OF LUEDERS, TEXAS.

COVERLET-HOLDER.

1,106,474.

Specification of Letters Patent. Patented Aug. 11, 1914.

Application filed January 23, 1914. Serial No. 813,829.

To all whom it may concern:

Be it known that I, GOTTFRID PERSSON, a citizen of the United States, residing at Lueders, in the county of Jones and State 5 of Texas, have invented certain new and useful Improvements in Coverlet-Holders of which the following is a specification.

My invention relates to a new and useful coverlet holder, and its object is to provide 10 a device that will serve to support a coverlet or quilt at a slight elevation above a bed, so that the same will not have contact with any person occupying the bed, allowing him to repose in greater comfort.

15 Another object of my invention is to provide simple and convenient means for accomplishing a vertical adjustment of the coverlet holder, so that the space intervening between the coverlet and the occupant 20 of the bed may be increased or diminished.

A still further object of the invention is to provide a device of the character described that will be strong, durable, efficient and simple and comparatively inexpensive to 25 produce, also one in which the several parts will not be likely to get out of working order.

With the above and other objects in view, the invention has relation to certain novel 30 features of construction and operation, an example of which is described in the following specification and illustrated in the accompanying drawings, wherein:

Figure 1 is a view showing my coverlet holder in side elevation, together with a bed with which the device is correlated. Fig. 2 is a transverse vertical sectional view of the same, the section being taken upon the line $x-x$ of Fig. 1. Fig. 3 is a detail top view of 35 a joint established between two of the parts of my invention. Fig. 4 is a view showing in side elevation a modified form of my invention. Fig. 5 is a transverse vertical sectional view taken upon the line $y-y$ of Fig. 40 Fig. 6 is an end view of the coverlet holder omitting certain yoke members forming a part thereof and omitting the bed. Fig. 7 is a detail sectional view taken upon the line $z-z$ of Fig. 6. Fig. 8 is detail 45 sectional view taken upon the line $a-a$ of Fig. 6. Fig. 9 is a detail view showing a portion of one of the yokes which are embodied in my coverlet holder and which each carry several fastening devices for engaging 50 the coverlet. Fig. 10 is a detail sectional view taken upon the line $a-a$ of Fig. 6. Fig. 11 is a detail view showing a portion of one of the yokes which are embodied in my coverlet holder and which each carry several fastening devices for engaging 55 the coverlet. Fig. 12 is a detail sectional

view, the section being taken upon the line $b-b$ of Fig. 2.

Referring now more particularly to the drawings, wherein like reference characters designate similar parts in all the figures, the numerals 1 and 2 respectively designate the head and foot of a bed, and 3 is the horizontal body portion of the bed, which extends between the members 1 and 2. It is to be understood that the bed comprising the 60 parts 1, 2 and 3 may be either of wood or metal and may have any desired design.

To each end of the bed and preferably equidistant from its sides there is vertically secured a tubular standard 4 provided with a rigid base 5, which is fastened to the body 3 by straps 5^a, or other suitable means. The upper portion of each standard 4 receives the lower end portion of a vertical rod 6, a rigid relation being maintained between the 65 parts 4 and 6 by a set screw 7. Adjacent to the upper extremity of each rod 6, there is rigidly mounted a bracket 8, with which there is integrally formed a bifurcated upwardly extending arm 9. Above the bed 70 comprised by the members 1, 2 and 3, and between the upper extremities of the rods 6, there is extended an elongated member 10 preferably of tubular construction, from the extremities of which there rigidly projects 75 rods 11 terminating in eyes 12 through which the upper ends of the rods 6 are passed. The rods 11 are each received between the furcations of the correlated member 9, and are given a rigid relation with the members 80 9 by bolts 13 which are passed through the parts 9 and 11. Upon the member 10, there are pivotally hung a plurality of triangular frames, each comprising parts 14, 15 and 16. Each member 14 is formed at its upper extremity with an eye receiving the member 10, and at its lower extremity is rigidly connected with the center of an elongated horizontal rod 15 mounted transversely of the 85 bed, and extending the entire width of the 90 same. From the extremities of each member 15, there are extended inclined brace wires 16 to the upper end of the correlated member 14. Each member 15 is formed with a plurality of equally spaced depending 95 lugs 16^a, through each of which there is passed a leather loop 17, the extremities of which are connected by some suitable form of buckle, as for example that designated at 100 18. From each loop 17, there is swung a 105 110

fastening device 19 comprising two adjacent downwardly projecting portions one of which terminates in an open ring 20. Said portions as they extend downwardly will preferably diverge slightly from each other as is clearly illustrated in Fig. 9. Upon each member 19, there is loosely mounted a link 21 which through a downward displacement will serve to bring the lower ends of 10 the member 19 together engaging the coverlet or other fabric which is interposed between said parts.

In that modification of my invention which is illustrated in Figs. 4 to 10 inclusive, 15 standards 22 provided with bases 23 are respectively secured to the extremities of the bed comprised by the parts 1, 2 and 3, as in the first described case. Above the bed and between the upper extremities of the standards 22, there is extended an elongated horizontal member 24 having arms 25 projecting rigidly from its end. Upon the free end of 20 each arm 25 there is pivotally carried a collar 26, which slidably engages the upper portion of the correlated standard 22.

In one of the collars 26, there is mounted a set screw 27 which will serve to hold said collar rigid with the correlated standard in various positions of vertical adjustment. 25 Upon the lower portion of the other standard 22 there is mounted fast a semi-circular bracket 28, having its extremities connected by an approximately diametrical bar 28^a. Upon the member 28^a, there is centrally pivoted a lever 29, with which there is intermediately pivotally connected the lower end of a swinging bar 30, having its upper extremity pivotally attached to the collar 26 mounted upon said standard 22. By subjecting the lever 29 to an angular displacement about its pivoted end, it is apparent that the correlated collar 26 will be subjected to a vertical sliding displacement upon said standard 22. In 40 order to hold the lever 29 in various positions of angular displacement, there is correlated with said lever a smaller pivoted lever 31, carrying upon one of its extremities a tooth 32, which may be engaged in any 45 one of the plurality of apertures 32^a formed in the quadrant 28. The toothed end of the lever 31 is acted upon by a spring 33 which tends normally to hold the tooth 32 engaged in one of the apertures 32^a. In this instance, there are mounted upon the member 24 a plurality of yokes 34, which take the place of the triangular frames described in the first form of the invention. From each of the yokes 34 there is suspended a plurality 55 of the fastening devices comprised by the parts 17, 18, 19, 20 and 21, such as has been already described. Preferably one of these devices will be carried by each extremity of each yoke 34 and one will be suspended from 60 the center of each yoke.

In using my above described invention, the coverlet or quilt will be engaged by each of the fastening devices 19, and said devices will serve to hold the fabric spread substantially horizontally above the occupant 70 of a bed.

The adjustability of the standards in both forms of my invention is desirable mainly to adjust the device for use in conjunction with beds of various designs and sizes. This adjustability is furthermore advantageous however in disposing the coverlet or quilt at such an elevation above the occupant of a bed that it will carry out its proper function in retaining heated air beneath the coverlet without resting upon the occupant of the bed or in any way inconveniencing him. 75

In addition to the uses above set forth, my invention may have a utility also in supporting a mosquito netting to protect the 80 occupant of a bed from mosquitoes and other insects.

The invention is presented as including all such modifications and changes as properly come within the scope of the following 85 claims.

What I claim is:

1. In a device of the character described, the combination with a pair of standards respectively secured to the extremities of a 95 bed, of an elongated member extending horizontally above the bed between said standards, a plurality of elongated members pivotally supported by the first specified member and disposed transversely of the bed 100 above the same, and a plurality of fastening devices carried by each transverse member.

2. In a device of the character described, the combination with a pair of standards extensible in length and respectively secured to the extremities of a bed, of an elongated horizontal member extending above the bed between said standards, a plurality of elongated transverse members pivotally supported by the first specified member above the 105 bed, and a plurality of fastening devices carried by each of said transverse members.

3. In a device of the character described, the combination with a pair of standards respectively secured to the extremities of a bed, 115 of an elongated member extending horizontally above the bed between said standards, means for manually subjecting said member to a vertical adjustment, a plurality of elongated members extending transversely of the bed above the same and pivotally supported by the first specific elongated member, and a plurality of fastening devices carried by each transverse member.

4. In a device of the character described, 125 the combination with a pair of standards respectively secured to the extremities of a bed, of an elongated horizontal member extending above the bed between the two standards, a triangular frame pivotally sup- 130

ported by said elongated member comprising a rigid vertical member depending from said elongated member, a member transverse of the bed to which the lower extremity of the vertical member is rigidly secured, and wires extending between the extremities of the transverse member and the upper end of the vertical member, and a plurality of fastening devices carried by said frame.

5 10 15 5. In a device of the character described, the combination with a pair of extensible standards respectively secured to the extremities of a bed, of an elongated horizontal member extending above the bed between said standards, and a plurality of fastening devices supported by said member.

6. In a device of the character described, the combination with an elongated horizontal member extending above a bed between the extremities thereof, of a plurality of 20 elongated members mounted transversely of the bed and pivotally supported by the first specified elongated member, and a plurality of fastening devices carried by the transverse members.

25 In testimony whereof I have signed my name to this specification in the presence of two subscribing witnesses.

GOTTFRID PERSSON.
